PHOTOGRAPHIC COPY ATTACHMENT FOR A CAMERA OR SIMILAR ARTICLE

Grant H. Muse, Jr., Englewood, Colo.

Application March 24, 1958, Serial No. 50,148

Term of patent 7 years

(Cl. D61—1)

The single figure is a perspective view of a photographic copy attachment for a camera or similar article, showing my new design.

The broken line showing of a representative camera is for illustrative purposes only.

The opposite side, not shown, has substantially the same appearance as the side shown in the figure.

I claim:

The ornamental design for a photographic copy attachment for a camera or similar article, substantially as shown and described.
